UNITED STATES PATENT OFFICE.

WILLIAM C. HUGHES, OF NEW HAVEN, CONNECTICUT.

CLOTHES DRIER.

1,422,061.

Specification of Letters Patent.

Patented July 4, 1922.

Application filed December 18, 1920. Serial No. 431,650.

To all whom it may concern:

Be it known that I, WILLIAM C. HUGHES, a citizen of the United States, residing at New Haven, in the county of New Haven and State of Connecticut, have invented certain new and useful Improvements in a Clothes Drier; and I do hereby declare the following to be a full, clear, and exact description of the invention, such as will enable others skilled in the art to which it appertains to make and use the same.

This invention relates to a clothes drier, and more particularly to a device designed for attachment to a window frame.

15 The object is to provide, in connection with an outwardly extending supporting element, a slideable drying frame, with particular means for moving the latter toward and away from the window frame.

20 A further object is to provide a collapsible drying frame, means for mounting the latter for movement toward and away from the wall of a building, and devices for supporting the mounting means with reference 25 to the wall.

A still further object is to provide a device which shall include a transverse bar for connection with the wall on the opposite sides of a window frame, a supporting element constituting a supporting frame and having rigid connection with the bar, a collapsible drying frame carried by the supporting frame, and a threaded element for moving the drying frame toward and away 35 from the window.

With the foregoing and other objects in view, the invention consists in the novel construction, combination, and arrangement of elements hereinafter described and claimed, 40 it being understood that modifications may be made within the scope of the claims, without departing from the spirit of the invention.

In the accompanying drawings:

45 Figure 1 is a top plan view of a clothes drier constructed in accordance with my invention.

Figure 2 is a view in side elevation of a clothes drier.

50 Figure 3 is a sectional view taken on a vertical plane extending centrally and transversely through the clothes drier.

Figure 4 is a sectional view on the plane indicated by the line 4—4 of Figure 1.

55 Figure 5 is a sectional view taken on the plane indicated by the line 5—5 of Figure 1.

Figure 6 is a sectional view taken on the plane indicated by the line 6—6 of Figure 1, and

Figure 7 is a sectional view taken on the plane indicated by the line 7—7 of Figure 1.

Mounted transversely of the frame 10 of a window, and at a suitable distance above the sill 11, is a bar 12 rigidly secured in position and having mounted thereon a number of fixtures including pulleys 15, for use in connection with lines 15'.

Extending perpendicularly with reference to bar 12 is a hollow supporting frame 16, although comprising a pair of parallel elements 17 and 18, spaced apart and serving to mount the drying frame per se. An element 19 provided with a bore 20 is located between the outer ends of elements 17 and 18, and passing loosely therethrough is a 75 bar 22 constituting one of the principal elements of the drying frame.

The frame just referred to further includes collapsible arms 24 and 25, connected by the cords 26 upon which the garments are 80 to be hung. It will be understood that when the device is not in use, the cables 26 and 15' may be disengaged from certain of the pulleys and the arms 24 folded outwardly toward one another while the arms 25 are 85 folded inwardly towards the sides of the supporting frame 16.

A threaded member 30 between the inner ends of elements 17 and 18 receives the main screw, or threaded rod 31 operated by a 90 detachable handle or crank 32, the outer end of this screw passing to the guiding element 33 slideable between the elements 17 and 18 of the hollow supporting frame 16. This guiding element 33 is rigid with reference 95 to bar 22, and the frame or more particularly the element 25' thereof is rigid with reference to member 33, so that upon the rotation of the screw in one direction, the entire frame is carried outwardly, sliding 100 along the hollow supporting frame 16,—or if the direction of rotation of the screw is reversed the frame is caused to move inwardly, and toward the window.

An eye bolt 35 on the hollow supporting 105 frame 16 provides means for connecting a guy wire 36 with the window frame, for supporting the drier in the correct position. Another guy wire, serving a similar purpose is designated 38 and connected with the 110 outer ends of the arms 24 and with the window frame 10.

Having thus described the invention, what I claim is:—

1. In a device of the class described, an element to be mounted transversely of a window frame, a supporting frame extending perpendicularly with reference thereto, a drying frame slideable with reference to the supporting frame, said drying frame including a guiding element slideable in the supporting frame, and a rotatable threaded member for imparting movement to the drying frame through the guiding element. 50
2. In a device of the class described, an element to be mounted transversely of a window frame, a supporting frame rigidly connected therewith and including a guiding device at its outer end, a drying frame including a guiding device slideable in the supporting frame, and a rotatable threaded member for imparting movement to the drying frame through the guiding element carried thereby. 55
3. In a device of the class described, a bar for connection with the wall of a building on opposite sides of a window frame, means for connecting a clothes line with said bar, a supporting frame extending perpendicularly with reference to the bar and rigidly connected therewith, said supporting frame comprising a pair of spaced parallel members, a drying frame slideable along the supporting frame, a guiding member carried by the drying frame and directly engaging the supporting frame, said drying frame including a central bar connected with the guiding element, a second guiding member mounted at the outer end of the supporting frame and cooperating with the central bar of the drying frame, and a threaded rod for imparting movement to the drying frame through the guiding member first named. 70
4. In a device of the class described, a bar to be mounted transversely of a window frame, a supporting frame comprising a plurality of spaced parallel members rigidly 75

connected with the bar, a threaded member between the spaced members, a slideable guiding member movable along the supporting frame including a central portion extending between the spaced members, a screw passing through the threaded member and imparting movement to the guiding member, a drying frame with which the guiding member is connected, said drying frame including a central bar connected with the guiding member, and a second guiding member, mounted at the outer end of the supporting frame and cooperating with the central bar of the drying frame. 80

5. A clothes drier comprising a supporting frame, a drier frame adjustable on said supporting frame and including collapsible members, a stationary supporting bar adapted to be secured to a wall, cable connections between said collapsible members, and cable connections between one of said collapsible members and said supporting bar. 85

6. A clothes drier comprising a supporting bar, a supporting frame mounted on said supporting bar, said supporting bar being adapted to be secured to a stationary support, a drier frame adjustable on said supporting frame and carrying clothes receiving and supporting members, and clothes receiving and supporting members extended from said drier frame to said supporting bar. 90

7. A clothes drier comprising a supporting bar adapted to be secured to a stationary support, a supporting frame mounted on said supporting bar, an adjustable drying frame mounted on said supporting frame, connections between said drying frame and said supporting bar, and means to adjust said drying frame on said supporting frame. 95

In testimony whereof I affix my signature in presence of two witnesses.

WILLIAM C. HUGHES.
